UNITED STATES PATENT OFFICE.

DAILY S. MOORE, OF CHICAGO, ILLINOIS, ASSIGNOR OF TWO-THIRDS TO
ABNER PRICE AND ALEXANDER PRICE, OF SAME PLACE.

RAILWAY-TRACK LAYER.

SPECIFICATION forming part of Letters Patent No. 408,186, dated July 30, 1889.

Application filed September 11, 1888. Serial No. 285,110. (No model.)

To all whom it may concern:

Be it known that I, DAILY S. MOORE, a citizen of the United States, residing at Chicago, in the county of Cook and State of Illinois, 5 have invented certain new and useful Improvements in Railway-Track Layers, which are fully set forth in the following specification, reference being had to the accompanying drawings, forming a part hereof, and in 10 which—

Figure 1 shows my improved machinery for laying railway-track in side elevation. Fig. 2 shows the same in plan. Fig. 3 shows the upper end of my new side stake and bracket 15 on the stake and my new tie-carrier in end view, with its new roller and chain belts and rollers to hold said tie-carrier. Fig. 4 shows the end of the bracket over the stake in section, so as to show its interior construction 20 and the part upon which the tie-carrier rests in a modified form from that shown in Fig. 3. Fig. 5 shows a fragment of a roller in my tie-carrier with its chain-pulleys, &c., in enlarged 25 detail. Fig. 6 is a side view of a splicing-plate used to join successive sections of carriers.

The object of my invention is to improve the construction of the mechanism for the same purpose for which Letters Patent were granted to me February 1, 1887, and numbered 30 356,777 and 379,178, March 6, 1888.

It being found somewhat unsafe as well as impractical to run the ties over the heads of the men working on the rail and supply cars in front, to overcome said difficulties, I 35 construct my improved machinery substantially as follows—namely: I use the same arrangement of flat cars *a b c, &c.*, but provide the front car *a* with a set of two or three tall posts *d* on each side, and to them I bolt horizontal bars *d'*, which are left to project over the side of the car *a* a sufficient distance to hold both sides of the tie-carrier *e* in line with the tie-carriers on the outside of the tie-carrying cars in the rear part of the train, forming a part 40 of my complete mechanism. Said tie-carrier *e* is bolted securely to said cross-bars, and the said six posts are further secured by horizontal tie-rods or wire ropes *d''* at their top, as shown, so as to be firmly braced.

50 To the front end of the carrier *e* is attached

a carrier *e'*, which is hung so that its front or outer end shall be over the center of the track, and which may be raised and lowered at its outer end by means of the ropes *e''*, attached to it and fastened to the upper ends of inclined posts *e'''*. The upper ends of said posts are held in place each by a pair of braces *e''''* from the tops of the front posts *d*, and the carrier *e'* is further braced by a brace *e'''''* from the opposite post *d*, as shown. 55

To the rear end of the carrier *e* is attached a carrier *f* by means of splicing-plates *m* of any suitable form, preferably such as are shown in Fig. 6, which have slots through which the bodies of the bolts pass into the 60 sides of the carriers, which thereby permit sufficient longitudinal motion for adjustment, but hold the ends of adjacent carrier in line, and which may be held at any point by drawing the bolt-heads firmly on the plates, and 65 near the rear end of said carrier is attached a clevis *f'* over the outer sides of the carriers, to which a wire rope *f''* is attached, which passes over a diagonal brace from the foot of the post *d* on the car *a*, and said rope is secured at the top of said post *d*, so as to hold the rear end of said carrier to the front end of the carrier *g* of the car *c*. Said carrier *f* is therefore carried entirely by the car *a*, and tends thereby to balance the overhanging 70 weight in front of the car. The car *c* has stakes *c'* set into the stake-pockets, with which such cars are usually provided, and said stakes are provided on their outer sides with notches or upwardly-pointing serrations *c''*. 75

A bracket *h*, having a hole at one end, through which said stake can pass, is placed upon each of the two posts *c'*, placed on the third and each car back of it in the train and 80 in line with the carrier *e*. Said bracket has a lip *h'* projecting inward into the stake-hole, which passes into one of the notches *c''* and securely holds it at any desired point on the said stake. The side of the hole opposite said 85 lip *h'* projects back from the post a distance slightly greater than the length of the lip, but slants upward toward the post and presses against it at its upper end, which, with the lip diagonally opposite, tends to hold the bracket 90 95 100

level. By this arrangement it is only necessary to raise the outer end of the bracket until the lip is out of the notch to either raise or lower the bracket, and to bring it to the horizontal position to secure it at any point. Said bracket is provided with a roller *i*, which carries the carriers *g*, also with horizontal rollers *i'* on the outer sides of the carriers. Said rollers serve to allow freer motion longitudinally to said brackets under the carriers as the cars are pushed together or drawn apart in the train, and thereby to ease the lateral strain on said brackets.

The carriers are provided with rollers *j*, which are provided at one end with a pair of connected sprocket-wheels *j'* and flanges *j''* between them, and also at both their outer ends. Said construction is, besides being more economical, also easier working. The chain belts pulling against each other in a more direct line relieve the axles of much friction. One of said rollers *j* of the carrier *e* is fixed to a shaft *j''*, projecting across the car *a*, on which is a pulley connected to an engine, through which all the rollers in the connected series of carriers are operated, and by means of which the ties thrown upon them are carried to the front and dropped on the road-bed from the front of the carrier *e'*. All the carriers have similar sides *e''*, and are alike provided with rollers *j* and chain belts, as already shown and described.

What I claim is—

1. In a railway-track layer, in combination with the carriers *g*, the brackets *h* and stakes *c'*, provided with notches *c''*, substantially as specified. 35

2. In a railway-track layer, the combination of the notched stake *c'* with a bracket provided with lip *h'*, substantially as specified. 40

3. In a railway-track layer, in combination with the carrier *g*, the adjustable carriers *f e'*, fixed carrier *e*, and car *a*, substantially as specified.

4. In a railway-track layer, in combination with the car *a*, provided with posts *d* and fixed carrier *e* outside of said posts, the adjustable carrier *e'*, attached to the front of said fixed carrier, whereof the front is over the center line of the car, posts *e''*, braces *e''*, 50 and ropes *e''*, substantially as specified.

5. In a railway-track layer, in combination with the car *a*, provided with posts *d* and fixed carrier *e* outside of said posts, the adjustable carrier *e'*, provided with brace *e''*, 55 posts *e''*, and braces *e''*, substantially as specified.

DAILY S. MOORE.
